UNITED STATES PATENT OFFICE

139,092

DESIGN FOR A TEAPOT OR SIMILAR ARTICLE

Rudolph V. Ganz, Zanesville, Ohio, assignor to Shawnee Pottery Co., Zanesville, Ohio

Application June 29, 1944, Serial No. 114,256

Term of patent 14 years

(Cl. D44—26)

To all whom it may concern:

Be it known that I, Rudolph V. Ganz, a citizen of the United States, residing at Zanesville, in the county of Muskingum, and State of Ohio, have invented a new, original, and ornamental Design for a Teapot or Similar Article, of which the following is a specification, reference being had to the accompanying drawings, forming part thereof.

Figure 1 is a front elevational view of a teapot or similar article, showing my new design, Figure 2 is a rear elevational view thereof, Figure 3 is a side elevational view, and Figure 4 is a top plan view.

I claim:

The ornamental design for a teapot or similar article, as shown.

RUDOLPH V. GANZ.
